RAILWAY TRUCK

Glenn F. Couch, Rochester, N. Y., assignor to
The Symington-Gould Corporation, Rochester,
N. Y., a corporation of Maryland

Application November 2, 1934, Serial No. 751,203

13 Claims. (Cl. 105—197.1)

This invention relates to railway trucks and, more particularly, to the construction of the side frames, bolsters and spring nests thereof for supporting such bolsters from said frames.

5 The principal object of my invention, generally considered, is the provision of a railway truck in which the side frames are readily detachable, and in which the bolster is supported by springs which cooperate with one another in order to 10 increase the capacity of the arrangement as the load is increased.

Another object of my invention is the provision of a railway truck in which the bolster is supported from the side frames by both coil and 15 leaf springs, the central portion of the leaf spring being at approximately the center of the frame and the end portions disposed either longitudinally or laterally thereof, and the coil springs being vertically disposed with respect to portions 20 of said leaf spring between the center and end portions so that said leaf spring assists in the actuation of said coil springs.

A further object of my invention is the provision of a railway truck in which the ends of the 25 bolster are received in castings or saddles which are, in turn, supported by leaf or semi-elliptic springs therebeneath and coil or helical springs, vertically disposed with respect to intermediate portions of said leaf springs, so that said bolster is initially supported by said leaf springs until 30 they are deflected a predetermined amount to actuate said coil springs.

A still further object of my invention is the provision of a railway truck in which the bolster 35 is supported by both coil and leaf springs, and in which the bolster may angle in a horizontal plane with respect to the associated frames.

Other objects and advantages of the invention relating to the particular arrangement and construction of the various parts will become apparent as the description proceeds.

Referring to the drawings illustrating my invention, the scope whereof is defined by the appended claims:—

45 Figure 1 is a fragmentary side elevational view of a railway truck embodying my invention, the position of the bolster being that when it is supported entirely by the semi-elliptic springs under light car conditions.

50 Figure 2 is a fragmentary plan of the truck shown in Figure 1.

Figure 3 is a fragmentary longitudinal sectional view of one of the truck frames on the line 3—3 of Figure 2, looking in the direction of the 55 arrows, the position of the bolster with respect

to the frames being that under the condition of an increase in the lading so that the semi-elliptic spring bears against the helical spring caps.

Figure 4 is a view corresponding to Figure 3, but showing the position of the bolster when the 5 car is loaded still further, or until the bolster supporting casting contacts with the extended tops of the helical spring caps.

Figure 5 is a view corresponding to Figure 4, but showing the final stage in which the helical 10 springs have been pushed away from their contact with the semi-elliptic spring after contact between the spring caps and bolster supporting casting.

Figure 6 is a view corresponding to Figure 1, 15 but showing another embodiment of my invention.

Figure 7 is a fragmentary transverse sectional view of the truck on the line 7—7 of Figure 6, looking in the direction of the arrows. 20

Referring to the drawings in detail, like parts being designated by like reference characters, and first considering the embodiment of my invention illustrated in Figures 1 to 5, inclusive, there is shown a portion of a railway vehicle or 25 truck comprising side frames 1, only one of which is illustrated, each side frame having a compression member or portion 2, a tension member or portion 3, and spaced connecting struts, bolster guide columns, or portions 4 spacing intermediate 30 portions of said compression and tension members, and leaving a bolster or window opening 5 therebetween.

The tension member 3 is formed with horizontal shelves or abutment portions 6 adjacent 35 the junctions with the guide columns and normally engaged by the ends of the leaf or semi-elliptic spring 7 disposed in the bolster opening 5 and, in turn, supporting a frame or saddle member 8 having a downwardly opening pocket 40 9 receiving the upper portion of the semi-elliptic spring band 10, thereby preventing undesired displacement therebetween.

The saddle member or casting 8 has a normally horizontal portion 11 on which rests the adjacent end portion of the bolster 12 and side portions 13 normally embracing said end portion therebetween. Rear guide lugs 14 only are provided on said bolster. 45

The saddle or casting 8 is guided between the 50 guiding portions 15 of the guide columns 4 by extending between the flanges 16 of said guide columns and having outstanding rib or flange portions 17 adapted to slide on the transverse guiding surfaces of the guide portions 15. 55

The tension member 3 is formed with upwardly opening pockets 18 on the lower web 19 thereof receiving coil or helical springs 20, only one of which is illustrated, which support spring 5 caps 21 upwardly extended to underlie the saddle casting 8 and be received in downwardly opening pockets 22 thereon. Each spring cap 21 is apertured, as indicated at 23, to receive the semi-elliptic spring 7 which extends therethrough and 10 through the inner webs 24 of the guide columns so as to reach the supporting shelves 6. The relation between the springs, spring caps and bolster saddle is such that under light car conditions the bolster is supported by the semi-elliptic 15 springs 7 only, the saddle 8 not engaging the extended spring caps 21, and the elliptic springs 7 not engaging the bosses 25 on the helical spring-engaging webs 26 of the spring caps 21.

Although I do not show the ends of a frame, I 20 contemplate the provision of journal boxes integral therewith, such journal boxes and end portions not being shown as they may be of conventional construction. Provision for out-of-squareness or flexibility of the truck is effected 25 by connection between the bolster and frames or supporting saddles, such flexibility being provided by forming the surfaces 27 of the bolster, which are disposed between and normally engaged by the surfaces 28 of the saddle or casting 30 8, cylindrical, and the surfaces 28 coaxial therewith, with the axis of said surfaces inside of the center line of the side frame so that the bolster can be withdrawn, said axis being also desirably on the central longitudinal vertical plane of the 35 bolster.

The surfaces 27 and 28 terminate at their outer ends in portions 29 and 30 which together provide generally cylindrical pockets receiving locking members 31. Each locking member desirably 40 comprises a normally vertical cylindrical body 32 and a lower laterally extending lug 33, and is desirably initially inserted with the lug extending outward or away from the bolster, the saddle 8 being provided with an elongated aperture 34 45 adapted to receive said body and lug portions. When the locking member 31 has been inserted so that the lug lies above the horizontal portion 11 of the saddle, the locking member is then turned, so that the lug points inward or toward 50 the other locking member (not illustrated), while the bolster is elevated, so that when the bolster is dropped to position, as shown in Figure 1, the lug portion 33 is received in a pocket 35 in the lower side of the bolster and securely held in 55 place. Sufficient clearance is provided between the locking members 31 and the bolster to allow for the desired flexibility or angling in a horizontal plane while preventing undesired displacement or withdrawal of the bolster.

60 From the foregoing disclosure, it will be seen that I initially provide for the support of the bolster by abutments 6 disposed toward the ends of the frames, thereby greatly decreasing the bending moments on said frames. As the semi-elliptic spring in each frame is deflected upon an 65 increase of the load applied to the bolster, the semi-elliptic spring bears upon the helical spring caps 21, as illustrated in Figure 3, at points intermediate its center and ends. During this stage, 70 the helical springs 20 are not deflected to the same degree as the semi-elliptic spring 7, because the latter is temporarily a double lever of the second class. In other words, if the spring band 10 is depressed one-quarter inch, after engagement between the semi-elliptic spring 7 and the 75

caps 21, the coils are compressed approximately one-half this amount, the arrangement between the coil and semi-elliptic springs being thus temporarily a series-parallel arrangement.

As the bolster moves further downward, the 5 saddle casting 8 contacts with the extended tops of the helical spring caps, as shown in Figure 4, whereupon both types of springs are deflected, upon further downward movement of the bolster exactly the same amount until the final stage 10 shown in Figure 5 is reached, in which the helical spring caps have been pushed away from their contact with the semi-elliptic spring.

It is believed that this is an entirely new arrangement of differential spring travel, starting 15 first with a simple semi-elliptic spring serving to support the bolster, then picking up helical springs and moving them only half as fast as the semi-elliptic spring, and finally progressing to a straight parallel arrangement. This combination provides for the gradual building up of 20 spring capacity at a faster ratio than that of either a straight series or straight parallel spring arrangement, and without the sudden augmentations of capacity characteristic of stepped spring 25 groups where the shorter springs are placed under initial compression.

Referring now to the embodiment of my invention illustrated in Figures 6 and 7, there is shown an arrangement which amounts to an 30 inversion of the embodiment of Figures 1 to 5, inclusive, as far as the nests of springs is concerned. As in the first embodiment, I show a portion of a railway truck comprising side frames 1^a, only one of which is illustrated, each side 35 frame having a compression member 2^a, a tension member 3^a, and spaced connecting struts, bolster guide columns, or portions 4^a spacing intermediate portions of said compression and tension members, and leaving a window or bolster opening 40 5^a therebetween.

In the present embodiment, the side frames may be of conventional character, or as shown in my Patent No. 1,652,808. Resting on the tension members of the frames is a spring plank 36, as 45 distinguished from the first embodiment which is illustrated without a spring plank. Said plank has corrugations 37 providing grooves or pockets receiving the auxiliary reinforcements 38 of the side frame and serving to interlock the spring 50 plank to said frame. Resting on the plank is a spring pan or abutment casting 38' desirably formed with corresponding pockets or channels 39 to receive the embossments 31 on the plank for maintaining the desired relationship. The pan 55 38' is formed with a generally central abutment portion 40 providing an upwardly opening pocket 41 receiving the spring band 10^a of a semi-elliptic spring 7^a serving to initially support under light load conditions the associated bolster 12^a 60 by engaging abutment portions 6^a thereon.

The bolster is formed with downwardly opening pockets 18^a on the upper web 19^a thereof receiving coil or helical springs 20^a which pass through the lower web 42 of the bolster and 65 whose axes desirably lie in the central longitudinal vertical plane of said bolster and rest on lower spring caps 21^a downwardly extended, and with their lower ends fitting in upwardly opening pockets 22^a on the pan 38'. The lower 70 surfaces of said caps are desirably initially spaced from the supporting surfaces of the pan and the upper ends of said springs 20^a initially spaced from the lower surfaces of the upper web 19^a of the bolster.

Each cap 21^a is apertured, as indicated at 22^a, to receive the semi-elliptic spring or springs 7^a which extends therethrough to reach the abutments 6^a. The relation between the springs, 5 spring cap, bolster and pan is such that under light car conditions, as illustrated, the bolster is supported by the semi-elliptic springs at each end only, the springs 20^a not engaging the bolster but the caps 21^a being supported on the semi- 10 elliptic spring and held out of supported engagement with the pan 38.

As the semi-elliptic spring 7^a is deflected upon an increase of the load applied to the bolster, the upper web of said bolster approaches the 15 tops of the originally free helical springs 20^a, but the latter recede downward from the descending bolster at about one-half the bolster speed because their inverted caps or seats are temporarily resting on intermediate points on the upturned 20 semi-elliptic spring.

When the bolster top web touches the helical springs 20^a, but before the helical seat castings touch bottom, we have a series parallel arrangement between the springs comparable with that 25 illustrated in Figure 3, where the semi-elliptic springs act as double levers of the second class, resulting in compression of the coils at a rate approximately one-half the rate of deflection of the semi-elliptic spring.

30 When the helical seat castings touch bottom, then we have parallel action between all the springs because contact between the semi-elliptic spring and the helical spring seats is broken and all springs deflect at the same rate until final closure.

40 In the present embodiment, the bolster is provided with conventional outer guide lugs 43 and inner guide lugs 14^a which cooperate with the bolster guiding portions 15^a in a conventional manner for maintaining the desired relation between the bolster and frame, as will be understood.

45 Although preferred embodiments of my invention have been disclosed, it will be understood that modifications may be made within the spirit and scope of the appended claims. It will also be understood that both embodiments may involve journal boxes integral with or separable from the end portions of the frames, as may be desired.

50 I claim:—

1. In a railway truck, in combination, a side frame formed with compression and tension members spaced at intermediate portions by guide 55 columns, leaving a bolster opening therebetween, spring means disposed in the lower portion of said opening, other spring means vertically disposed with respect to said first-mentioned spring means, and a bolster initially supported on said 60 first-mentioned spring means only, whereby said first-mentioned spring means, after being deflected a predetermined amount, actuates the other spring means for a predetermined distance, after which the bolster positively actuates said 65 other spring means so that it is supported by both of said spring means acting in parallel.

2. In a railway truck, in combination, a side frame formed with compression and tension members spaced at intermediate portions by 70 guide columns, leaving a bolster opening therebetween, a spring supported by said frame, spring means disposed below said first-mentioned spring and between said guide columns and so arranged, that the spring serves to support an associated bolster under light load, and upon be-

ing deflected a predetermined amount, actuates said spring means in series-parallel therewith until positive engagement is effected between the bolster and said spring means, so that said bolster is supported by said spring and spring means 5 acting in parallel.

3. In a railway truck, in combination, a side frame formed with compression and tension members spaced at intermediate portions by guide columns, leaving a bolster opening therebetween, a spring supported by said frame, spring means disposed above said first-mentioned spring and so arranged that the spring serves to support an associated bolster under light load, and upon being deflected a predetermined amount 10 actuating said spring means in series-parallel therewith until direct engagement is effected between the bolster and said spring means, so that said bolster is supported by said spring and spring means 15 acting in parallel. 20

4. In a railway truck, in combination, a side frame formed with compression and tension members spaced at intermediate portions by guide columns, leaving a bolster opening therebetween, a semi-elliptic spring disposed in the lower portion of said opening and with its ends extending beneath said guide columns, helical springs vertically disposed with respect to said semi-elliptic spring, and a bolster initially supported on said semi-elliptic spring only, whereby the 25 semi-elliptic spring, after being deflected a predetermined amount, serves as a lever acting on the ends of said helical springs for actuating the same for a predetermined distance, after which positive engagement is effected between the 30 bolster and said helical springs, so that said bolster is supported on said semi-elliptic and helical springs acting in parallel. 35

5. In a railway truck, in combination, a side frame formed with compression and tension 40 members spaced at intermediate portions by guide columns, leaving a bolster opening therebetween, a semi-elliptic spring supported by said frame, a saddle supported by said spring, helical springs, spring caps extending upwardly from 45 said helical springs, normally spaced from abutment portions on said saddle, and apertured for the passage of said semi-elliptic spring, said helical springs being arranged below said semi-elliptic spring, whereby the semi-elliptic spring 50 and saddle serve to support an associated bolster under light load, and upon said spring being deflected a predetermined amount, said spring directly engages abutments on said helical spring 55 caps for actuating said helical springs in series-parallel with said semi-elliptic spring until said spring caps engage said abutment portions and the bolster is supported by said semi-elliptic and helical springs acting in parallel.

6. In a railway truck, in combination, a side 60 frame formed with compression and tension members spaced at intermediate portions by guide columns, leaving a bolster opening therebetween, a spring plank received in said opening and supported on said tension member, a spring 65 pan disposed on said plank, a semi-elliptic spring with a band resting on said pan and extending transversely of the frame, a bolster disposed above said semi-elliptic spring, and normally engaging the ends thereof for being supported solely thereby under light load, said bolster having downwardly opening pockets, coil springs disposed in said pockets, lower spring caps supporting said coil springs and, in turn, supported on said semi-elliptic spring under light load, said 70 75

- coil springs under light load being spaced from the upper wall of said bolster and said caps being then spaced from supporting surfaces of said pan, and the initial clearances being such that 5 upon the semi-elliptic spring being deflected a predetermined amount it causes the coil springs to engage the upper wall of the bolster for actuation in series-parallel therewith, resulting finally in the spring caps engaging supporting surfaces 10 on the pan, to cause said coil springs to then act in parallel with said semi-elliptic spring.
7. In a railway truck, in combination, a side frame formed with compression and tension members spaced at intermediate portions by 15 guide columns, leaving a bolster opening therebetween, a semi-elliptic spring supported by means of said tension member, coil springs supported one between each end and the center of said semi-elliptic spring and vertically disposed 20 with respect to said spring, a bolster, a bolster-supporting saddle casting upheld under light load by said semi-elliptic spring only and by all of said springs upon sufficient increase in the bolster load.
- 25 8. In a railway truck, in combination, a side frame formed with compression and tension members spaced at intermediate portions by guide columns, leaving a bolster opening therebetween, a semi-elliptic spring supported by said 30 tension member and provided with a spring band, a casting with a downwardly opening pocket receiving the upper portion of said band and initially supported by said spring, said casting having side portions, a bolster resting on said casting and formed with lugs for limiting relative movement therebetween, and coil springs disposed 35 beneath said semi-elliptic spring and provided with spring caps through which said semi-elliptic spring passes, which caps extend upwardly to underlie surfaces on the casting so that, when sufficient additional load is applied on the bolster, said coil springs come into action for the support thereof.
9. A side frame for railway trucks formed with 45 compression and tension members spaced at intermediate portions by guide columns, leaving a bolster opening therebetween, said tension member having upper and lower webs, said upper web being apertured adjacent said guide columns to 50 receive helical springs and permit them to be supported on said lower web, said tension member also having shelves disposed longitudinally of the frame, beyond said bolster opening, for direct support of the ends of a leaf spring.
- 55 10. A spring nest adapted for insertion in the bolster opening of a railway vehicle side frame comprising a set of leaf springs and a set of helical springs and associated caps, characterized by the helical springs being vertically disposed with 60 respect to portions of said leaf springs interme-

diate the centers and ends, and said leaf springs passing through apertures in said caps, with sufficient initial clearance provided, so that said leaf springs initially act independently of the helical springs and after a predetermined deflection take up the clearance and bring said helical springs into action.

11. A spring nest adapted for insertion in the bolster opening of a railway vehicle side frame comprising a set of leaf springs and a set of helical springs with caps, said sets being vertically disposed with respect to one another and arranged so that clearance is provided between the bolster and one of said sets and between said sets so that under light load one set only acts, then as 15 the load increases the clearance between the sets is taken up and both sets act in series-parallel, and, upon increasing the load still further, said clearance with respect to the bolster is taken up so that both sets act in parallel.

12. In a railway truck, in combination, a side frame formed with tension and compression members spaced at intermediate portions by guide columns to leave a bolster opening therebetween, spring means supported by said tension member, a casting initially supported by said spring means, said casting having side portions, a bolster supported by said casting and formed with lugs overlying said side portions for limiting relative movement therebetween, additional 25 springs disposed beneath said spring means and provided with spring caps initially engaging the first-named spring means and means on said cap which extend upwardly and underlie a portion of said casting, said extensions being also 30 initially spaced therefrom, whereby said last-mentioned springs come into action for the support of said bolster when sufficient additional load is applied thereto.

13. In a railway truck, in combination, a side frame comprising tension and compression members spaced at intermediate portions by guide columns to leave a bolster opening therebetween, spring means supported by said tension member, a casting initially supported by said spring means, a bolster supported by said casting, side portions on said casting interposed between the guide columns and bolster, lugs on said bolster overlying said side portions for limiting relative movement between the bolster and casting, an additional spring disposed beneath said spring means and provided with a spring cap having a lower portion thereof interposed between said springs and supported by said additional spring; said spring cap having an upper portion thereof underlying and normally spaced from said casting so that when sufficient additional load is supplied to the bolster said additional spring comes into action for the support thereof.

GLENN F. COUCH. 60
